UNITED STATES PATENT OFFICE.

JOSEPH CLOVIS ARTHUR BONENFANT, OF MONTREAL, QUEBEC, CANADA.

ROLLING DOOR.

Application filed March 2, 1920, Serial No. 362,751. Renewed June 23, 1924.

To all whom it may concern:

Be it known that I, JOSEPH CLOVIS ARTHUR BONENFANT, a subject of the King of Great Britain, and residing at 675 Notre Dame Street, East, in the city and District of Montreal, in the Province of Quebec, in the Dominion of Canada, have invented a new and useful Rolling Door, of which the following is the specification.

10 The invention relates to rolling doors as described in the present specification and illustrated in the accompanying drawings that form part of the same.

15 The invention consists essentially in the novel means employed whereby the operation is much facilitated.

20 The objects of the invention are to eliminate the manual exertions required in opening and closing fire box and other doors; to increase the efficiency in firing for steaming purposes; to furnish a door that may be opened coincident with the operations in feeding and instantaneously closed at each operation; to devise a simple and effective 25 mechanism, which lessens the force required for the initial effort; and generally to provide a serviceable and durable rolling door.

20 In the drawings, Figure 1 is an elevation of the door and frame, showing a portion 30 of the frame and the rack rod connector broken away and also the front of the furnace shown broken away.

35 Figure 2 is a side elevation, showing the operating mechanism, and the door frame partly broken away and the gear mechanism disclosed.

40 Figure 3 is a side elevation, without the locking ring and disclosing a full view of segmental gear rack and actuating lever by removing a part of the casing.

Figure 4 is a perspective detail of the driven gear.

Figure 5 is a detail of the locking ring.

45 Figure 6 is detail of the operating pedal with connecting parts broken away.

Like numerals of reference indicate corresponding parts in each figure.

50 Referring to the drawings, the door 1 is formed in pivotally joined sections 2 rolling on the segmental rolls 3, to which the upper section is connected by the links 4. The links 4 and the ends 5 of the sections 2 are recessed on the inner sides to correspond to the periphery of the rolls 3.

55 The rolls 3 are fixedly mounted on the shaft 6 journalled in the bearings 7 extend-

ing from the door frame 8, the latter having the vertical slide grooves 9 at the sides for holding the sections 2 closely to their place in the operation of the door.

60 The segmental gear 10 and lever 11 are fixedly mounted on the shaft 6 outside the bearing 7 and preferably are integral with one another, that is to say, the segmental gear 10 has the lever lateral extension 11 65 therefrom to one side of the centre of said gear. The segmental gear 10 is secured to the shaft 6 by means of the set screw 12 through the boss 13 or in any suitable manner.

70 The rack and kicker bar 14 is preferably in one piece, having the teeth 15 on one side in the upper portion of the bar, the kicker head 16 projecting from the other side and having an inclined top surface 17 75 and the forked lower end 18.

75 The crank lever 19 is pivotally secured in the bracket 20 standing on the flooring in front of the furnace and engages at the one end the forked end 18 of the kicker bar 80 14 and is engaged at the other end by the foot pedal 21.

85 The kicker bar 14 engages the segmental gear 10 and is held to its engagement by the roller 22 journalled on the pin 23 85 projecting from the boss 24 on the door frame.

90 The head 16 is normally under the lever extension arm 11 and on raising the kicker bar 14 by pressing on the pedal 21, the inclined head 16 hits the arm 11 thereby turning the gear 10 and imparting to the door an initiatory movement, the further movement of the opening gear being continued by the engagement of the teeth of 95 the rack with the teeth of the segmental gear, but head 16 by hitting the arm 11 initiates the motion of segmental gear and consequently the rolling door and the strain of the starting movement incident to the 100 short leverage indicated by one half the diameter of the gear is overcome by increasing that leverage to the length of the extension arm. In addition, it may be said that the kick given by the head 16 to the 105 arm 11 materially adds to the ease in which the initial movement is accomplished by this invention.

110 The locking bar 25 is in three-quarter ring form and is formed with the radial slots 26 and lugs 27, 28, 29 and 30, said lug 30 forming the bearing for the outer end

of the pin 23 carrying the roller 22 between the boss 24 and lug 30, said lugs 27, 28 and 29 being secured to the door frame by the pins 31, thereby permitting ample room for the operation of the arm 11.

The locking bolt 32 is pivotally secured to the arm 33 fixedly mounted on the shaft 6 and swings into one or other of the slots 26 to lock the door to the open position desired.

The grooved pulley 34 is mounted on the other end of the shaft 6 and a chain 35 winds thereon and this chain is connected by the spring 36 to the lower end of the frame and winds on said pulley against said spring tension on the closing of the door and therefore forms a shock absorber and balance.

Various changes may be made in the construction of this invention without departing from the spirit of the invention, and so long as these changes are within the scope of the claims for novelty following, the protection accorded shall not be invalidated.

What I claim is:—

1. In a rolling door for a furnace, the combination with a plurality of sections and rolls, of a rack and gear operating mechanism having a lever extension from the gear coacting with a kicker extension from the rack in effecting the initiating movement in the opening of the door.

2. In a rolling door for a furnace, the combination with a plurality of sections and rolls, of a rack and gear mechanism in operative relation to said rolls, said rack

having a head projecting therefrom beneath an arm projecting from said gear.

3. In a rolling door for a furnace, the combination with a plurality of sections and rolls, of a rack and gear mechanism in operative relation to said rolls, said rack having a head with an inwardly sloping crown immediately under an arm forming part with the gear coacting with the rack.

4. In a rolling door for a furnace, a door formed in sections pivotally joined together and closing by gravity, a door frame, bearings supported by said frame, a shaft journalled in said bearings, segmental rolls mounted on said shaft and receiving said sections thereon in the opening movement, a segmental gear mounted on said shaft and having a lever extension arm therefrom, a kicker bar suitably operated at its lower end and terminating in a kicker head and having a rack on the inner side thereof coacting with said gear, a locking bar in part ring form rigid with the door frame and having slots and a coacting locking bolt rotatively secured to said shaft, said locking bar having outwardly projecting radial legs for connecting it to the frame and inwardly extending pin projection to the frame adjacent to said kicking bar, and a roller engaging said kicking bar and journalled on said pin projection and forming a keeper for said kicker bar.

Signed at the city of Montreal, Province of Quebec, Dominion of Canada, this 10th day of October, 1919.

JOSEPH CLOVIS ARTHUR BONENFANT.
